US0D1063956S

(12) **United States Design Patent** (10) Patent No.: **US D1,063,956 S**
(45) Date of Patent: ** Feb. 25, 2025

(54) **DISPLAY PANEL OR SCREEN OR PORTION THEREOF WITH GRAPHICAL USER INTERFACE**

(71) Applicant: **SONY GROUP CORPORATION**, Tokyo (JP)

(72) Inventors: **Chikako Yoshinaka**, Kanagawa (JP); **Taku Sugawara**, Tokyo (JP)

(73) Assignee: **SONY GROUP CORPORATION**, Tokyo (JP)

(**) Term: **15 Years**

(21) Appl. No.: **29/850,837**

(22) Filed: **Aug. 23, 2022**

(51) LOC (15) Cl. **14-04**

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display panel or screen or portion thereof with a graphical user interface as shown and described.

DESCRIPTION

FIGURE is a front view of a display panel or screen or portion thereof with a graphical user interface showing our new design.

The outermost broken lines shown in the drawing represent the display panel or screen or portion thereof with a graphical user interface that form no part of the claimed design. The broken lines in the animated graphical user interface illustrating portions of the graphical user interface form no part of the claimed design.
